UNITED STATES PATENT OFFICE

2,632,940

POWER FILING MACHINE

James Wingo, Jr., Cambridge, Mass., assignor of
one-half to John J. Roche, Brighton, Mass.

Application March 29, 1949, Serial No. 84,171

2 Claims. (Cl. 29—76)

1

This invention relates to a new and improved power filing machine and particularly to a portable filing machine adapted to be supported by the operator in contact with the surface to be filed. My improved machine embodies a power driven endless chain of pivotally connected links mounted on a portable frame. A file is attached to each link between the pivot axes and the arrangement is such that the combined files provide a straight and continuous filing unit along the filing reach of the chain and the files are adapted to pass freely about the chain supporting wheels at the ends of the frame. The production of a new and improved filing machine of this nature comprises the primary object of the invention.

The frame is provided with guiding channels along the filing reach and the links of the chain are constructed at their inner portions with flanges for engaging within these channels and at their outer portions with like flanges for supporting a file on each link. Adjacent links are connected by pivot pins and roller bushings are mounted on the pins between the links in position to rotate along said reach on a bridge disposed beneath and in position to contact and support the bushings. Thus the chain is guided along a straight path at the filing reach and the filing thrust is taken largely in an anti-friction manner by the roller bushings on the bridge. The production of an improved construction of this nature comprises a further object of the invention.

Further novel features of the invention include transversely extending and curved filing teeth on the files including cutting edges facing toward a handle at one end of the frame. The chain is drawn along the reach in the direction of the handle which in the grasp of the operator resists the longitudinal thrust of the machine.

These and other features of the invention will be best understood and appreciated from the following description of a preferred embodiment thereof selected for purposes of illustration and shown in the accompanying drawings, in which—

Fig. 1 is a side elevation of a filing machine embodying my invention.

Fig. 2 is a front end view.

Fig. 3 is a fragmentary section taken on line 3—3 of Fig. 1.

Fig. 4 is a fragmentary section taken on line 4—4 of Fig. 5.

Fig. 5 is a fragmentary side elevation of the front end of the machine.

Fig. 6 is a perspective view of one of the files employed, and

2

Fig. 7 is a side elevation of the machine illustrating preferred driving mechanism.

Referring more specifically to the drawings by reference characters, 10 indicates an oblong frame having two sprocket wheels 12 at its two ends. An endless chain 15 embodying pivotally connected links is supported on the wheels and extends lengthwise of the frame with one reach 16 disposed along the bottom face of the frame.

10 The chain 15 is constructed of links 18 connected by pivot pins 19. Each link embodies two U-shaped plates each having an intermediate portion 20, an inner leg or flange 21 and an outer leg or flange 22. The intermediate portions 20 are relatively long and form the side plates of the chain and the two side plates of each link are pivotally connected at their ends to the side plates of the adjacent links by pivot pins 19, the side plates being disposed in overlapping relation as illustrated in Figs. 3 and 4.

15 The bottom portion of the frame includes a guideway 24 for the bottom reach of the chain. This guideway is supported on the frame by legs 26 welded to the frame at 27. The guideway comprises a plate 28 extending longitudinally of the frame and provided with outer over-hanging side walls 30 providing two spaced open channels 31 facing each other across the plate 28. The channels are adapted to receive the flanges 21 and guide the chain therewith as illustrated in Figs. 20 3 and 5. The ends of the channels are flared outwardly to receive the flanges as illustrated in Fig. 5.

25 The two outer flanges 22 provide a platform for supporting a file 32 on each link. The files are of a size commensurate with each link between the pivot axes and are preferably of arcuate shape. The bottom face is adapted to rest flatly on the flanges 22 and to be secured thereto by rivets or screws 34. The outer face of the file is provided with arcuately curved filing teeth 36. The arrangement is such that the combined files provide a straight and continuous filing unit along the bottom reach 16, and the files are adapted to pass freely about the chain supporting 30 wheels 12 at the ends of the frame.

40 Each file 32 is substantially rectangular and extends transversely of the chain parallel with the pivot axes at 19. The file can be provided with teeth 36 on both faces if desired thus making the files reversible and doubling their useful life. The teeth 36 of the files on the chain all face in one direction and each tooth extends obliquely outwardly toward the two ends of the file and rearwardly away from said one direction. This 45 arrangement, shown as arcuately curved teeth 50 55

in Fig. 6, provides a draw cut outwardly toward the ends of the file.

A roller bushing 38 is mounted on each pivot pin 19 between the side plates of the link to provide roller bearings for supporting the link. A bridge 40 is mounted on the guide plate 28 beneath the bushings and is of a thickness to take the major thrust load when the files are in operation along the reach 16. Thus the flanges 21 in the channels 31 serve to guide the chain and the bushings riding on the bridge provide anti-friction bearing support for taking the thrust load.

The chain can be driven by suitable power means and I have illustrated for this purpose an electric motor 42 mounted on the frame as by brackets 44. Bevel gearing 46 in a gear box 48 connects the motor shaft 50 with a vertical shaft 52. The shaft 52 is supported in a bracket 54 on the frame and is provided with a bevel gear 56 in mesh with a larger bevel gear 58 fixed to the shaft 60 carrying one of the wheels 12. Two handles 62 and 64 carried by the gear box and motor are provided for manipulating the machine. The motor is preferably two-speed and reversible to provide for operating on work of varying character.

It is ordinarily desirable that the operating lengthwise thrust of the machine shall be in a direction away from the handle 64 and for this reason the files are usually applied to the links with the cutting edges of the teeth 36 along the filing reach 16 facing the handle 64. Also for this reason, it may be desirable to drive the chain from the other sprocket wheel 12 as illustrated in Fig. 7. In this case the positions of the motor and gear box are reversed to that shown in Fig. 1.

It will now be apparent that I have produced a compact and superior filing machine of the nature and for the purpose described. The endless link chain with a file attached to each link between the pivot axes provides a strong and rugged construction adapted to give efficient and continuous service. The novel construction of the links together with the guide carried by the frame facilitates the manufacturing and assembling operations required and produces a machine that functions with maximum ease and efficiency and with a minimum of power. It will furthermore be apparent that the arcuate arrangement of the filing teeth provides for a draw cut which promotes the successful operation of the machine.

Having thus disclosed my invention what I claim as new and desire to secure by Letters Patent is:

1. A filing machine comprising an oblong frame, two wheels mounted on the two ends of the frame, an endless chain embodying pivotally connected links supported on the wheels and extending lengthwise of the frame, one reach of the chain between the wheels being disposed along one face of the frame, a chain supporting guide-way on the frame extending along said reach and including two spaced U-shaped channels at opposite sides of the chain and having their open sides facing each other and having their walls connected by a plate rearwardly of and in supporting contact with the chain, outwardly extending flanges carried by the links and disposed within said channels along said reach, a handle on one end of the frame, a file attached to each link and having filing teeth facing outwardly of the frame and toward the handle end of the frame along said reach, and a motor carried by the frame for driving the chain toward the handle along said reach, each of said links embodying two U-shaped plates respectively at the two sides of the link, the intermediate portions of the plates providing the connecting side walls of the link, the inner legs providing said outwardly extending flanges disposed within said channels, and the outer legs providing a supporting platform for the file.

2. The filing machine defined in claim 1 in which said U-shaped plates of each link are pivotally connected at the ends by pins to the adjacent links, a roller bushing on each pin between the plates, and a bridge extending along said reach beneath and in position to contact and support the bushings.

JAMES WINGO, JR.
